UNITED STATES PATENT OFFICE

1,942,762

HOT BLAST STOVE

Frank R. McGee, Steubenville, Ohio

Application March 14, 1932. Serial No. 598,834

8 Claims. (Cl. 263—19)

This invention relates to hot-blast stoves, one of the objects being to provide quick initial ignition of the gases introduced to a stove's combustion chamber during its heating cycle. Another object is to cause a complete combustion of these gases before they reach the brick checkerwork in these stoves whereby the latter's life is prolonged. Other objects will be understood from the following description.

10 Having reference to the accompanying drawing, which illustrates a specific example of a hot-blast stove constructed according to this invention, Figure 1 is a cross-sectional side elevation and Figure 2 a cross-section on the line II—II of Figure 1.

The drawing shows a single-pass hot-blast stove that includes the usual brick checkerwork 1 positioned in a refractory lined casing 2. The casing 2 is constructed to provide a combustion chamber 3 above the checkerwork 1. This combustion chamber 3 has a cylindrical recess 4, a hot-blast conduit or main 5 leading from the end of this recess and gas inlets 6 being arranged in its sides. The products of combustion from the chamber 3 pass down through the brick checkerwork 1 and through an outlet 7.

When the brick checkerwork is hot a blast is blown up through it by means of a compressed air pipe 8, the hot-blast being carried through the conduit 5 to a furnace. After the blast has been blowing some time the brick checkerwork becomes cooled to a point where it becomes necessary to reheat it. This is generally done by mixing air and gas together in the chamber 3, the initial ignition of this mixture depending on the heat retained by this chamber's lining. This ignition will naturally occur more easily after the incoming air is heated. This is done by providing an air inlet 9 for the conduit 5 at a point remote from the chamber 3, this conduit having a cut-out valve 10 immediately beyond this inlet. At the beginning of the stove's heating cycle this valve 10 is closed and the air from the inlet 9 blown through a considerable length of the conduit 5. This conduit, being necessarily lined with refractory material, retains the heat from the hot blast blown through it for a considerable length of time, the air consequently being materially heated by passage therethrough and producing the desired result. Also, when the valve 10 is closed a column of the outgoing hot blast is trapped in the conduit 5. This intensely heated air further insures an immediate spontaneous combustion of the gases in the chamber 3.

55 The air stream coming from the conduit 5 into

the chamber 3 is at right angles to the gas streams coming from the gas inlets 6 so that the two gases mutually impinge. This also aids initial combustion and, in addition, insures complete combustion of the gases in the chamber 3 before they reach the brick checkerwork 1.

Otherwise than has been described, the operation of the stove follows customary practice. The gas inlet 6 communicates with the gas main 12 through a valve 13, and the outlet 7, air jet 8 and air inlet 9 are all provided with valves 14 for obvious reasons.

Although this specific form of hot blast stove has been shown and described in accordance with the patent statutes it is not intended to limit the scope of the invention exactly thereto, except as defined by the following claims.

I claim:

1. A hot-blast stove including brick checker-work, a combustion chamber for heating, said checker-work, a hot-blast main leading from said chamber, means for closing said main at a remote point from said chamber, means for passing air through said main to said chamber while said first named means is closed and means for introducing combustible gases to said combustion chamber.

2. A hot-blast stove including a combustion chamber, a hot-blast main leading from said chamber, one or more gas inlets in said chamber adjacent the mouth of said main and at right angles thereto, means for closing said main at a point remote from said chamber and means for introducing air to said main at a point adjacent said closing means when the latter is closed.

3. A stove including a regenerator, a combustion chamber communicating with said regenerator, a hot-blast main communicating with said chamber, means for introducing fuel to said chamber, a valve interposed in said main at a point remote from said chamber and means for introducing air to said main adjacent said valve when the latter is closed.

4. The method of operating a stove having an intercommunicating hot-blast main and combustion chamber, which includes the acts of closing said main at a point remote from said chamber and introducing the latter's air for combustion through the former.

5. The method of operating a stove having an intercommunicating hot-blast main and combustion chamber, which includes closing said main at a point remote from said chamber and introducing air into the main at substantially

atmospherically normal temperature, said air being introduced at a point sufficiently remote from said chamber to effect a heat exchange with said main sufficient to materially heat said air as it passes therethrough.

6. A single-pass, hot-blast stove including a checkerwork, a combustion chamber above said checkerwork and having a recess in its upper portion, and means for introducing mutually impinging air and gas to said recess.

7. A single-pass, hot-blast stove including a checkerwork, a combustion chamber above said checkerwork and having a recess in its upper portion, a hot-blast main opening into the upper portion of said recess and extending therefrom outside of the furnace, means for closing said main, means for introducing air to said main between the first named means and said recess, and means for introducing gas to said recess at

80

an angle to air coming through and from said main.

8. A single-pass, hot-blast stove including a checkerwork, a combustion chamber above said checkerwork and having a recess in its upper portion, a hot-blast main opening into the upper portion of said recess and extending therefrom outside of the furnace, means for closing said main, means for introducing air to said main between the first named means and said recess, and means for introducing gas to said recess at an angle to air coming through and from said main, the first and second named means being at a point remote from said recess whereby the air introduced by the second named means and coming through said main can absorb heat therefrom to aid initial ignition in said chamber.
